UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed December 7, 1923. Serial No. 679,056.

To all whom it may concern:

Be it known that I, LARS O. GRONDAHL, a citizen of the United States, residing at Pittsburgh, in the county of Allegheny and State of Pennsylvania, have invented certain new and useful Improvements in Railway-Traffic-Controlling Apparatus, of which the following is a specification.

My invention relates to railway traffic controlling apparatus.

I will describe several forms of traffic controlling apparatus embodying my invention, and will then point out the novel features thereof in claims.

In the accompanying drawings, Fig. 1 is a diagrammatic view showing one form of trackway apparatus suitable for controlling train carried governing means embodying my invention. Fig. 2 shows a modified form 20 of the trackway apparatus shown in Fig. 1. Figs. 3 and 4 are views showing two forms 25 of train carried governing means each suitable for co-operation with the trackway apparatus illustrated in Fig. 1. Fig. 5 is a view showing an arrangement of train carried governing means suitable for co-operation with the trackway apparatus shown in Fig. 2. Fig. 6 is a view showing 30 my invention applied to the control of the trackway signal.

Similar reference characters refer to similar parts in each of the several views.

Referring first to Fig. 1, the reference characters 1 and 1^a designate the track rails of a stretch of railway track over which traffic normally moves in the direction indicated by the arrow. These rails are divided, by means of insulated joints 2, into a plurality of track sections, of which one only, section A—B, is shown in the drawing. Located adjacent the entrance end of the section next in advance of section A—B is a three position signal S controlled by means not shown in the drawing. It is sufficient to state that when the corresponding section is occupied, the signal indicates stop; when the corresponding section is unoccupied and the next section in advance is occupied, the signal indicates caution; and when the corresponding section and the next section in advance are both unoccupied the signal indicates proceed. Means are provided for supplying section A—B with alternating track circuit currents of different frequen-

cies. For example, generator G may give 55 current of a comparatively high frequency and generator H current of a comparatively low frequency. These generators H and G may be of either the rotating or the electron tube type. A track transformer T is located 60 adjacent the exit end of section A—B, and has its secondary 3 constantly connected with the rails of the section. The primary of this track transformer is provided with a circuit which passes from generator G, 65 through wire 7, contact 8—9 operated by signal S, wire 10, primary winding 4 of transformer T, and wire 11 back to generator G. This circuit is closed only when signal S indicates caution or proceed. A 70 second track transformer T' has its secondary winding 5 connected across the rails at an intermediate point J in the section, and is supplied with energy over a circuit which starts with generator H and passes 75 through wire 12, contact 13—14 operated by signal S, wire 15, primary winding 6 of transformer T', and wire 16 back to generator H. This circuit is closed only when signal S indicates stop. It follows that section A—B is supplied with track circuit current of one frequency at point B by transformer T when signal S indicates proceed or caution, and with track circuit current of a different frequency at point J by 80 transformer T' when signal S indicates stop.

Referring now to Fig. 3, the train carried apparatus here shown comprises two magnetizable cores 17 and 17^a mounted transversely to the two track rails 1 and 1^a and 85 in inductive relation therewith. These two cores are carried in front of the forward axle 18 of the train. The cores 17 and 17^a are provided with two windings 19 and 19^a respectively so connected that the voltages 90 induced therein by currents flowing in opposite directions in the two track rails at any instant are additive. The two cores 17 and 17^a with their associated windings 19 and 19^a I shall collectively term the "pick-up coil." This pick-up coil supplies energy 95 to the primary 20 of a transformer K, and as here shown, suitable amplifying apparatus, is interposed between the two. Associated with secondary winding 21 of transformer K is a hot wire relay M, and associated with secondary 23 of transformer K is a similar hot wire relay N. Each of the

- hot wire relays M and N comprises an operating wire 24 and a contact finger 25 operated thereby. When wire 24 is cold, the wire contracts and opens contact 25-25^a, and when the wire 24 is heated, as by the passage of an electric current, the resulting increase in the length of the wire allows the associated contact 25-25^a to close. The operating wire 24 of relay M is connected across secondary 21 of transformer K and this circuit is tuned by means of a series condenser 21^a, to resonance at the frequency of the current supplied by generator G. In a similar manner operating wire 24 of relay N is connected with secondary 23 of transformer K and this circuit is tuned, by means of series condenser 23^a, to resonance at the frequency of the current delivered by generator H.
- 20 There are also provided on the train three indicators 26, 27 and 28 here shown as electric lamps and adapted when lighted to indicate "proceed," "caution," or "stop," respectively.
- 25 The circuit for stop lamp 28 passes from a battery 29, through wire 30, resistance 31, wires 32 and 33, lamp 28, and wire 34 back to battery 29. This circuit is closed at all times. Caution lamp 27 is provided with a circuit which passes from a battery 35, through wire 36, resistance 31, wires 32 and 41, lamp 27, wire 42, contact 25-25^a of hot wire relay N, and wire 40 back to battery 35. This circuit is closed only when current is flowing through operating wire 24 of relay N. Current is supplied to the proceed lamp 26 over a circuit which passes from battery 35, through wire 36, resistance 31, wire 37, lamp 26, wire 38, contact 25-25^a of relay M, and wires 39 and 40 back to battery 35. This circuit is closed only when current is flowing in the operating wire 24 of relay M.
- The parts are so proportioned and adjusted that when hot wire relays M and N are both de-energized current flows from battery 29 and energizes the stop lamp 28. If however, the circuit is closed for either of lamps 26 or 27, the voltage drop caused in resistance 31 by the passage therethrough of current from battery 35 is equal in magnitude and opposite in direction to the electromotive force supplied by battery 29 and hence neutralizes this latter electromotive force. Under these conditions lamp 28 is extinguished.
- In explaining the operation of the apparatus as a whole I will first assume that signal S in Fig. 1 is at proceed or caution. Track circuit current is therefore supplied to section A-B from generator G. If a train equipped with the apparatus shown in Fig. 3 enters the section, the current which will be induced in the track coil, will be amplified and supplied to the primary 20 of transformer K. Since the circuit including

secondary 21 of transformer K is tuned to resonance at the frequency of this current, there will flow in operative wire 24 of relay M a current of sufficient magnitude to close contact 25-25^a of this relay. As a result, lamp 26 will be energized, thus indicating proceed, and lamp 28 will be extinguished. This condition will continue as the train proceeds through section A-B.

I will next assume that signal S is at stop and that a train enters section A-B as before. The movement of signal S to stop disconnected generator G from transformer T and connected generator H with transformer T'. The train is therefore supplied with energy at the frequency of generator H between point A and J. Since the circuit including secondary 23 of transformer K is tuned to resonance at the frequency of generator H it follows that relay N will be energized while relay M will, of course, be de-energized. Current will therefore flow through the circuit for lamp 27 which will then be lighted to indicate caution, and the resulting voltage drop across resistance 31 will cause lamp 28 to be extinguished. As the train passes point J however, current is shunted away from the pick-up coil by the wheels and axles in rear of the coil and energy is no longer supplied to transformer K. Both relays M and N are therefore de-energized, lamps 26 and 27 are de-energized, and lamp 28 is lighted, thus indicating stop. A similar condition will result if the train is in an occupied section since the effect of the wheels and axles of the train ahead is to shunt the track circuit current from the pick-up coil and result in a stop indication.

Referring now to Fig. 4, only a portion of the apparatus is here shown, it being understood that the primary 20 of transformer K is connected, as in Fig. 3, with the pick-up coil. The apparatus of Fig. 4 is in all respects similar to that shown in Fig. 2 except that the batteries 35 and 29 are replaced in Fig. 4 by sources of alternating current such as the secondaries 44 and 45, respectively of a transformer D. The primary 43 of this transformer is constantly supplied with alternating current from a source not shown in the drawing. The two transformer secondaries 44 and 45 are so connected that the voltage drop through resistance 31 at any instant when either relay M or N is closed, is equal to, and of the opposite instantaneous relative polarity from the electromotive force of winding 45. The operation of the apparatus will be readily understood from the foregoing without further explanation.

In the modified form of trackway apparatus shown in Fig. 2, when signal S is at proceed or caution the circuit for transformer T is closed from one terminal of generator G, through wire 48, generator H, wire 47,

contact 8-9 operated by signal S, wire 46, primary 4 of transformer T, and wire 49 back to generator G. When this circuit is closed section A-B is supplied at point B 5 simultaneously with currents of two frequencies, that is, with one current of the frequency of generator G and with a second current of the frequency of the generator H. When signal S is at stop, a circuit is 10 closed over which energy flows from generator H, through wires 47 and 52, contact 14-13 operated by signal S, wire 51, primary 6 of transformer T' and wires 50 and 48 back to generator H. When this circuit 15 is closed current of one frequency only, (the frequency of generator H), is supplied to section A-B at point J.

One form of train carried apparatus for co-operation with the trackway apparatus of 20 Fig. 2 is shown in Fig. 5. In this view the relays M and N are controlled in the same manner as before but the energy for operating the various indicators is now supplied by a transformer P, the primary 53 25 of which is constantly supplied with alternating current from a source not shown in the drawing.

The proceed indicator 26 is controlled by a relay E over the following circuit: from 30 secondary 58 of transformer P, through wire 90, lamp 26, wire 89, front contact 88 of relay E, and wire 87 back to transformer secondary 58. This circuit is closed only when relay E is energized under which condition a proceed indication is received aboard the train. Relay E is constantly connected with the secondary winding 61 of a transformer L, having two primary windings 59 and 60. The caution lamp 27 40 is constantly connected with the secondary 64 of a transformer F provided with two primaries 62 and 63. The stop lamp 28 is controlled in part, as shall appear herein-after, by two transformers R and R'.

45 When relay M is energized a circuit is closed over which current flows from winding 56 of transformer P, through wire 72, contact 25-25^a of relay M, wire 73, primary 59 of transformer L, wire 74, primary 62 50 of transformer F, wire 75, primary 67 of transformer R', and wire 76, back to secondary 56 of transformer P. In a similar manner the energization of relay N closes a circuit over which current flows from secondary 57 of transformer P, through wire 80, primary 65 of transformer R, wire 79, winding 68 of transformer F, wire 78, primary 60 55 of transformer L, wire 77, contact 25-25^a of relay N, and wire 72 back to secondary 57 of transformer P. It will be seen that when relays M and N are both energized at the same time, the currents in primaries 59 and 60 of transformer L at any instant flow in the same direction, whereas the currents in 60 windings 62 and 63 of transformer F at any

instant flow in opposite directions. It follows that when either relay M or N is energized and the other is deenergized a current is induced in the secondary 64 of transformer F which lights lamp 27, but that when both these relays are energized simultaneously the magnetic fields due to currents in the primaries of transformer F tend to neutralize each other and hence lamp 27 is de-energized. The relay E however, is so 75 designed that when only one of the primaries 59 or 60 of transformer L is energized the energy induced in winding 61 of this transformer is not sufficient to energize the relay. If both windings 59 and 60 are simultaneously 80 energized, as by energization of both relays M and N, the effect of these windings is additive and relay E then becomes energized and completes the circuit for lamp 26, which 85 then becomes lighted.

The stop lamp 28 is constantly connected with secondary 55 of transformer P, the circuit passing from secondary 55, through wire 69, lamp 26, wires 70 and 86, resistance 31, and wire 71 back to secondary 55 of transformer P. Two relays O and Q are constantly connected with the secondary windings 68 and 66 of transformers R' and R, respectively. It is plain that when relay N is energized, the current flowing through primary 95 65 of transformer R, as explained hereinbefore, will cause relay Q to become energized and a circuit will be closed over which current flows from secondary 54 of transformer P, through wire 71, resistance 31, 100 wires 86 and 85, front contact 83 of relay Q, and wires 82 and 81 back to secondary 54 of transformer P. A branch is provided for this circuit which branch passes from wire 85, through front contact 84 of relay O, and 105 wire 81 back to secondary 54 of transformer P. Relay O is arranged to be energized, as will appear from the drawing, when relay M is energized. It is therefore plain that when relays M and N are both de-energized, 110 relays O and Q will both be de-energized, and stop lamp 26 will be lighted, but that when either or both of relays M and N are energized current will flow from secondary 54 of transformer P through resistance 31. 115 The parts are so proportioned that the voltage drop thus produced in this resistance at any instant is equal in magnitude and opposite in direction to the electromotive force of secondary 55 of transformer P and 120 lamp 26 is therefore extinguished.

I will now assume that signal S of Fig. 2 is at caution or proceed, and that a train equipped with the apparatus shown in Fig. 5 enters the section moving in the direction 125 of the arrow. As this train passes point A, primary 20 of transformer K will be supplied with currents of two different frequencies by generators G and H. Relays M and N are therefore both energized thus ener- 130

gizing relay E which in turn lights lamp 26. Under these conditions lamp 27 is extinguished and relays O and Q are both energized thus causing lamp 28 to be de-
5 energized.

I will next assume that signal S is at stop. If the train now enters the stretch at point A, transformer K will be supplied with alternating current of one frequency only from generator H. Since the circuit including the operating wire 24 of relay N is tuned to resonance at this frequency relay N becomes energized but relay M does not. Lamp 26 is therefore extinguished by the 10 de-energization of relay E. Lamp 27 is lighted however, thus indicating caution, and the energization of relay Q causes lamp 28 to be extinguished even though relay O is de-energized. As the train passes point 15 J, the supply of alternating current to transformer K is interrupted and relays M and N are both deenergized. Lamps 26 and 27 are therefore both de-energized, relays O and Q are both de-energized, and lamp 28 20 is lighted to give a stop indication.

The train carried apparatus illustrated in any of the views may be readily modified for use in connection with trackway signals, the apparatus shown in Fig. 6 illustrating the 25 governing apparatus of Fig. 3 applied to the control of a trackway signal C of the usual form. The three indicator lamps 28, 27 and 26 are here shown in a trackway signal C of the usual form and are controlled 30 in the manner already described by transformer K. The primary 20 of this transformer is connected, through suitable amplifying apparatus with the rails 1 and 1^a of the section A—B. A track relay W is 35 connected with the rails of the section to the right of B. When this relay is energized a circuit is closed over which current of one frequency flows from generator G through wire 98, front contact 91—92 of 40 track relay W, wire 95, primary 4 of transformer T, and wire 96 back to generator G. Current of one frequency is thus supplied to the apparatus at point A, and relay M, becoming energized lights lamp 26 to indicate 45 proceed. Under these conditions lamps 27 and 28 are extinguished.

In a similar manner when relay W is de-energized as by the presence of a train in the section to the right of B, current of a 50 different frequency flows from the generator H, through wire 94, back contact 91—92 of relay W, wire 95, primary 4 of transformer T, and wires 96 and 97 back to generator H. Current is then supplied to section 55 A—B by generator H and signal C displays a caution indication, lamp 27 being energized and lamps 26 and 28 being extinguished.

If section A—B is occupied by a train, 60 track circuit current will be shunted away

from primary 20 of transformer K irrespective of traffic conditions in advance of section A—B, and relays M and N both being de-energized, lamps 26 and 27 will both be de-energized and lamp 28 will be energized and signal C will display a stop indication. 70

Although I have herein shown and described only a few forms of apparatus embodying my invention, it is understood that 75 various changes and modifications may be made therein within the scope of the appended claims without departing from the spirit and scope of my invention.

Having thus described my invention, what 80 I claim is:

1. In a railway traffic controlling system, hot wire relays responsive to traffic conditions, a plurality of indicators controlled by such relays, means for constantly applying 85 an electromotive force to one said indicator, and means for neutralizing said electromotive force when any one of the remaining indicators is energized.

2. In combination, a stretch of railway 90 track, an indicator; a circuit for said indicator including a resistance, a source of electromotive force, and means responsive to traffic conditions in said stretch; a second indicator, and a circuit for said second indicator including said resistance and a second source of electromotive force so connected that the voltage drop in said resistance due to current flowing therethrough when said first circuit is closed is equal and opposite to 95 the electromotive force of said second source.

3. In combination, a stretch of railway 100 track, means for supplying said stretch with alternating current of one frequency or another depending on traffic conditions, two indicators, means for energizing one indicator or the other in accordance with the frequency of the current supplied to said stretch, a third indicator, a circuit for said 105 third indicator including a source of electromotive force, and means for neutralizing said electromotive force when either of said first two indicators is energized. 110

4. In combination, a stretch of railway 115 track, a transformer having a primary winding and two secondary windings, means for supplying said primary winding with alternating current of one frequency or another depending upon traffic conditions in said stretch, a first circuit including a secondary winding of said transformer and tuned to resonance at one said frequency, a first indicator controlled by said first circuit, a second circuit including a second secondary winding of said transformer and tuned to resonance at said second frequency, a second indicator controlled by said second circuit, a third indicator, and means for energizing 120 said third indicator only when said first in- 125

dicator and said second indicator are both de-energized.

5. In combination, a stretch of railway track, a first contact and a second contact

controlled in accordance with traffic conditions in said stretch, a first indicator; a circuit for said indicator including a source of energy, a resistance, and said first contact; a second indicator; a circuit for said second indicator including said source, said resistance and said second contact; a third indicator, and a circuit for said third indicator including said resistance and a second source of energy.

15. 6. In combination, a stretch of railway track, a first contact and a second contact controlled in accordance with traffic conditions in said stretch, a first indicator, a circuit for said indicator including a battery, a resistance, and said first contact; a second indicator; a circuit for said second indicator including said resistance, said battery, and said second contact; a third indicator, and a circuit for said third indicator including a second battery and said resistance.

7. In combination, a stretch of railway track, a first contact and a second contact controlled in accordance with traffic conditions in said stretch, a first indicator; a circuit for said indicator including a source of alternating current, a resistance and said first contact; a second indicator; a circuit for said indicator including said source, said battery and second contact, a third indicator; and a circuit for said third indicator including a second source of alternating current and said resistance.

8. In combination, two hot wire relays, means for selectively energizing said relays, two indicators one controlled by each said relay, and a third indicator arranged to be energized only when said first two indicators are deenergized.

45. 9. In combination, a transformer, means for at times supplying the primary of said transformer with alternating current, a secondary on said transformer connected with the operating wires of a hot wire relay and tuned to resonance at the frequency of said current, a contact controlled by said wire, an indicator controlled by said contact, and a second indicator arranged to be de-energized only when said first indicator is energized.

55. 10. In combination, two relays adapted to be selectively energized, an indicator constantly connected with a source of energy, a second and a third indicator, means for energizing said second indicator when either of said relays is energized, means for energizing said third indicator when both said relays are energized, and means for de-energizing said first indicator when either or both of said two relays are energized.

60. 11. In combination, two circuits tuned to

resonance at different frequencies, means controlled by traffic conditions for at times supplying each such circuit with current of its resonant frequency, a transformer, means controlled by one said circuit for supplying 70 alternating current of one relative polarity to one winding of said transformer, means controlled by the remaining said circuit for supplying alternating current of the other relative polarity to a second winding on said transformer, an indicator, and a third winding on said transformer for controlling said indicator.

12. In combination, two circuits tuned to resonance at different frequencies, a transformer, means controlled by one said circuit for supplying alternating current to one winding of said transformer, means controlled by the remaining said circuit for supplying alternating current to a second 85 winding on said transformer, an indicator, and a third winding on said transformer for controlling said indicator.

13. In combination, two circuits tuned to resonance at different frequencies, a transformer, means controlled by one said circuit for supplying alternating current of one relative polarity to one winding of said transformer, means controlled by the remaining said circuit for supplying alternating 90 current of the same relative polarity to a second winding on said transformer, an indicator, and a third winding on said transformer for controlling said indicator.

14. In combination, two circuits tuned to resonance at different frequencies, a transformer, means controlled by one said circuit for supplying alternating current to one winding of said transformer, means controlled by the remaining said circuit for supplying alternating current to a second winding on said transformer, an indicator, and a third winding on said transformer arranged to energize said indicator only when said first winding and said second winding 105 are both supplied with alternating current.

15. In combination, two circuits tuned to resonance at different frequencies, a transformer, means controlled by one said circuit for supplying alternating current of one relative polarity to one winding of said transformer, means controlled by the remaining said circuit for supplying alternating current to a second winding on said transformer, a third winding on said transformer, and a relay controlled by said third winding 115 for controlling said indicator.

16. In combination, two circuits tuned to resonance at different frequencies, a transformer, means controlled by one said circuit for supplying alternating current of one relative polarity to one winding of said transformer, means controlled by the remaining said circuit for supplying alternating current to a second winding on said 125 transformer, and a relay controlled by said third winding for controlling said indicator.

- transformer, and a third winding on said transformer for energizing said indicator when either said first or said second winding is energized but not when both such windings are energized.
17. In combination, two circuits tuned to resonance at different frequencies, two transformers, means controlled by each said tuned circuit for supplying alternating current to a winding of a corresponding one of said transformers, an indicator constantly connected with a source of energy, and means for de-energizing said indicator when alternating current is being supplied to either or both of said transformers.
18. In combination, two circuits tuned to resonance at different frequencies, two transformers, means controlled by each said tuned circuit for supplying alternating current to a winding of a corresponding one of said transformers, two relays, one connected with the secondary of each transformer, an indicator constantly connected with a source of energy, and means controlled by said relays for at times de-energizing said indicator.
19. In combination, two circuits tuned to resonance at different frequencies, two transformers, means controlled by each said tuned circuit for supplying alternating current to a winding of a corresponding one of said transformers, two relays, one connected with the secondary of each transformer, an indicator, a supply circuit for said indicator including a source of energy, and means effective when either or both of said relays are energized for imposing upon said supply circuit an electromotive force equal in magnitude and opposite in direction to the electromotive force of said source.
20. In combination, two circuits tuned to different frequencies, a relay controlled by
- each circuit and arranged to be energized only when current of the proper frequency is being supplied to the associated circuit, a first indicator arranged to be energized when either of said relays is energized but de-energized when both are energized, a second indicator arranged to be energized only when both said relays are energized, a third indicator constantly connected with a source of energy, and means for de-energizing said third indicator when either of the other indicators is energized.
21. In combination, a stretch of railway track, means for selectively supplying said stretch with alternating current of different frequencies, a trackway signal comprising an indicator constantly connected with a source of energy, a plurality of other indicators for said signal, means responsive to the presence and the frequency of current in the rails of the section for selectively energizing said latter indicators, and means for de-energizing said first indicator when any of the remaining indicators is energized.
22. In combination, two hot wire relays, means for selectively energizing said relays, an indicator constantly connected with a source of electromotive force, and means controlled by said relays for at times neutralizing said electromotive force.
23. In combination, two hot wire relays, means for selectively energizing said relays, an indicator, a circuit for said indicator including a source of electromotive force, and means controlled by said relays for at times supplying to said circuit a second electromotive force opposite in direction and substantially equal in magnitude to said first electromotive force.

In testimony whereof I affix my signature.
LARS O. GRONDAHL.
